(57) **CLAIM**

The ornamental design for a chemistry container for a reprocessor for decontaminating medical, dental and veterinary instruments and articles, as shown and described.

DESCRIPTION

FIG. 1 is a perspective view of a chemistry container for a reprocessor for decontaminating medical, dental and veterinary instruments and articles showing my new design;

FIG. 2 is a top plan view thereof;

FIG. 3 is a side view thereof, the opposite side being a mirror image thereof;

FIG. 4 is an end view thereof, the opposite end being a mirror image thereof; and,

FIG. 5 is a bottom view thereof.
